UNITED STATES PATENT OFFICE.

JOHN O. HEINZE, JR., OF DETROIT, MICHIGAN, ASSIGNOR TO GENERAL MOTORS COMPANY, OF DETROIT, MICHIGAN, A CORPORATION OF NEW JERSEY.

ROTARY PUMP.

1,132,263.

Specification of Letters Patent. Patented Mar. 16, 1915.

Application filed January 14, 1914. Serial No. 811,992.

To all whom it may concern:

Be it known that I, JOHN O. HEINZE, Jr., a citizen of the United States of America, residing at Detroit, in the county of Wayne 5 and State of Michigan, have invented certain new and useful Improvements in Rotary Pumps, of which the following is a specification, reference being had therein to the accompanying drawings.

10 The invention relates to rotary pumps of a type frequently used for propelling the water in the circulating system of an engine cooler and for similar purposes. In the present state of the art it is usual to 15 form the casings for such pumps of die castings. My improved construction is lighter and less expensive to manufacture, by being formed of sheet metal stampings.

In the drawings: Figure 1 is an elevation 20 of one of the half sections of the casing; Fig. 2 is a cross section on line $x-x$ Fig. 1; Fig. 3 is a section on line $y-y$; and Fig. 4 is a perspective view of the guard plate for the inlet connection.

25 A is a sheet metal stamping formed with a circular chamber B for receiving the rotary impeller, and with a hub portion C projecting therefrom and returning at D to form a bearing for the impeller shaft, and the 30 stamping is also provided with a tangential outlet passage E and a radial inlet passage F, while a peripheral flange G serves for bolting or otherwise securing the section to a duplicate complementary part.

35 To produce an operative rotary pump, it is necessary to direct the inlet passage to the center of the impeller and to shield this passage from the centrifugal force of the rotating water at the periphery. Such a construction cannot, however, be formed from 40 a single stamping without great complexity in the forming dies. I have therefore devised a construction in which a shield or deflector formed of a separate stamping is attached to the main stamping and covers the 45 inlet passage at the periphery. As specifically shown, H is a stamping which is of a cross section corresponding to that of the main stamping at the periphery of the central chamber B. This stamping H is placed 50 in a recess formed in the main stamping, so as to centrally cover the inlet opening F and to extend inward along the side. The recess I in which the stamping H is placed

is of the proper depth so that the inner face 55 of said stamping H is flush with the inner face of the portion of the main stamping forming the walls of the chamber B. The inlet passage F is however sufficiently embossed to extend around the deflector, as 60 indicated at F', and thus the water entering through the passage F will be directed toward the center of the chamber B before it comes in contact with the impeller. I preferably attach the stamping H to the main 65 stamping by spot-welding.

With the construction as described the weight of the casing is reduced from that necessary with a die casting, and the cost of manufacture is also reduced.

What I claim as my invention is,—

1. In a rotary pump, the combination with a casing formed of a sheet metal stamping having a chamber therein for the impeller and inlet and outlet passages communicating with said chamber, of a shield or deflector for completing the peripheral wall of said chamber opposite the inlet passage and deflecting the ingress to the center 70 of said chamber.

2. In a rotary pump, the combination with a casing formed of a sheet metal stamping having a circular embossed portion forming a chamber for the rotary impeller, a tangential outlet passage connecting with said 75 chamber and a radial inlet passage, of a deflector for completing the peripheral wall of said chamber opposite said radial inlet passage and deflecting the latter to the side thereof.

3. In a rotary pump, a casing formed of a sheet metal stamping having a circular embossed portion forming a chamber for the impeller, a tangential outlet passage communicating with said chamber and a radial 85 inlet passage, and an auxiliary sheet metal stamping secured to the main stamping forming a continuation of the peripheral wall of said central chamber opposite the radial inlet and deflecting the liquid passing 90 through the latter to one side thereof.

4. In a rotary pump, a casing formed of a sheet metal stamping having a circular embossed portion forming a chamber for the impeller and a radial inlet passage, and 105 an auxiliary stamping engaging a recess in said main stamping to form a continuation of the peripheral wall of said chamber flush

with the inner face thereof and extending up the side to deflect the liquid in said inlet toward the center of said chamber.

5. In a rotary pump, a casing formed of a sheet metal stamping having a central chamber, a tangential outlet and a radial inlet, with a projecting marginal flange for connection of said stamping with a complementary stamping, and an auxiliary stamping fitting in a recess in the wall of said main stamping and forming a shield or deflector, and continuing the peripheral wall of said chamber across said inlet and directing the liquid in the latter toward the center
- 10 of said chamber.
- 15

6. In a rotary pump, a casing formed of sheet metal stamping having a central chamber and inlet and outlet passages connecting therewith, and an insert in the wall of said casing forming a bridge across said inlet passage for continuing the peripheral wall of said chamber and deflecting the liquid in said inlet toward the center of said chamber.

In testimony whereof I affix my signature in presence of two witnesses.

JOHN O. HEINZE, JR.
